U.S. Cl. D2—409

Fig. 1

Fig. 2

Fig. 3

Fig. 4

Fig. 5

Fig. 6

Fig. 7

FIG. 1 is a front elevational view of a fastener fitting or similar article, showing my new design;

FIG. 2 is a rear elevational view thereof;

FIG. 3 is a side elevational view thereof, the opposite side being a mirror image thereof;

FIG. 4 is a top plan view thereof;

FIG. 5 is a bottom view thereof;

FIG. 6 is a cross-sectional view taken along line VI-VI of FIG. 3; and

FIG. 7 is a cross-sectional view taken along line VII-VII of FIG. 3.

I claim:

The ornamental design for a fastener fitting or similar article, substantially as shown and described.
